UNITED STATES PATENT OFFICE.

JAMES M. TEAHEN AND WILLIAM TAYLOR, OF DETROIT, MICHIGAN; SAID TAYLOR
ASSIGNOR TO SAID TEAHEN.

COMBINED WATER-CLOSET BOWL AND TANK.

Application filed May 25, 1925. Serial No. 32,844.

The invention relates to water closets of that type in which the flushing tank is located but slightly above the water seal level in the bowl, the requisite velocity for flushing being obtained by siphonic action.

The present invention is an improvement on the construction shown in the patent to James M. Teahen and W. Taylor No. 1,419,328 of June 13, 1922, and the invention 10 consists in various features of construction as hereinafter set forth.

In the drawings;

Figure 1 is a vertical central section through the combined bowl and tank.

15 Figure 2 is a horizontal section through a portion of the tank.

Figure 3 is a vertical section therethrough.

Figure 4 is a sectional plan view in the plane of the rim flush.

20 Figure 5 is a section on line 5—5 of Figure 1.

In the construction of the patent above referred to the flushing tank is integral with the bowl and located so as to be within the 25 space limits of standard roughing-in dimensions. The flushing is effected by introducing water from the tank into the bowl below the water seal and in sufficient volume to raise the level within the bowl so as to 30 establish siphonic action. This is the equivalent of raising the head so that a high velocity is imparted to the water entering the bowl and passing through the trap to accomplish a thorough flushing. The patent 35 referred to also shows a tangential arrangement of the passage for the water into the bowl to impart a rotary movement to the mass of water therein. This is for the purpose of establishing centrifugal and centripetal action within the bowl but we have 40 discovered that such action must be accurately controlled in order to produce beneficial results. Thus, if the rotary motion is too high in velocity, it will throw the water 45 up the sides of the bowl and produce a vortex that defeats the object of establishing siphonic action. On the other hand, if no rotary movement is imparted to the mass, the flushing action is not as efficient.

50 It is one of the features of the present improvement that the water entering the bowl is so directed and controlled as to produce just the requisite velocity of rotation. This is such that centrifugal action of the 55 water will produce a centripetal force for carrying the mass to the centre of the bowl so that it is first drawn through the trap.

Another feature of our improvement is in the construction of rim flush for washing the walls of the bowl which is such as to 60 produce a substantially equal distribution of a limited quantity of water around all sides of the rim, this water being directed downward against the walls of the bowl to produce an equal washing effect on all portions 65 thereof. Other features of our improvement will be referred to specifically hereinafter.

In detail A is a bowl which is supported on a pedestal B having arranged therein the trap comprising the upwardly and rearwardly extending leg C, the downwardly extending leg D and a laterally extending portion E which connects with the soil pipe. The tank F extends rearwardly from the trap B and also laterally to a greater width 70 than the bowl, its walls tapering forwardly to merge into the walls of the bowl. Surrounding the top of the bowl is a rim G which is hollow and provided with an inwardly extending portion G' on its underside and a series of jet apertures H which are inclined to be directed against the walls of the bowl. At the rear of this rim is an inlet passage I extending into the tank and adapted for connection with the water supply fitting. Within the hollow rim and extending around the rear portion thereof is a series of baffle plates J separated from each other sufficiently for the passage of a small amount of water therebetween but 75 directing a large portion of the stream to the opposite sides of the rim so as to insure substantially equal distribution to all of the jets H. The bottom of the tank F is preferably located but slightly below the level of 80 the water seal in the bowl and has provided therein at one point an aperture K which connects with the passage L extending at one side of the pedestal and communicating with a port M in the side of the bowl. As shown 85 in Figure 5 the passage L in the portion communicating with the port M is so fashioned that the stream of water entering the bowl is directed toward the central portion of the mass but slightly to one side of the 90 geometrical centre. This will produce a whirling of the water which however is limited in velocity so as to avoid interference with the establishment of siphonic action.

Nevertheless the rotary movement is suffi- 95

cient to produce a centrifugal and centripetal action above referred to which greatly assists the flushing action. The passage L is also connected with an upwardly extending passage N within the tank F, this rising to a point slightly above the normal level within the tank but lower than the top of the rim of the bowl. Thus, should water rise to an abnormal height due to a leaky inlet 10 valve or any other cause, it could overflow through the passage N and escape by way of the bowl and trap.

The port K which connects the tank with the passage L is controlled by a valve O which engages a seat member P. This seat member is preferably provided with a down turned flange P' extending into the aperture K, and a gasket Q between the seat member and the bottom of the tank forms 20 the seal. The seat member is secured in position by bolts R which pass through apertures in the bottom of the tank and engage nuts that are located in the passage L. Gaskets S normally prevent any leakage around 25 these bolts but should leakage at any time occur, it would be into the passage L which has free connection with the drain. The seat member P is provided with an upwardly extending post T at one side thereof which 30 is turned inward at its upper end and is provided with guide bearings U for engaging the stem O' of the valve O. V is an operating lever fulcrumed at V' upon the bracket W at one side of the tank and having at its 35 free end a loop V² for loosely engaging the stem O' below the loop or head O² at the upper end of said stem. The lever V may be operated by a handle X which has a crank arm X' connected by the link Y to said lever.

40 Water is supplied to the tank and to the rim through suitable connections which form the subject matter of another application for patent and therefore will not be described in detail. Generally these consist of an inlet conduit Z passing upward through the bottom of the tank and having at its upper end a fitting Z' containing the ball cock. This fitting is connected with the downwardly extending discharge conduit or hush tube Z² and the laterally extending conduit Z³ leading to the passage I in the rim. There is also a vent passage Z⁴ so located that it will normally discharge water when the ball cock is open but will act as an air vent in case of suction in the supply conduit Z.

In operation, the ball cock automatically admits water to the tank up to a predetermined level and also when open supplies a limited quantity of water to the hollow rim. 50 The flushing is effected by operation of the handle X connected to the crank arm X' and link Y, which lifts the stem O' and valve O connected therewith permitting the water to flow through the passage L and 55 port N into the bowl and this raises the

level within the bowl to a point where siphonic action is established whereupon the full volume of water in the bowl and tank is rapidly discharged at high velocity. This, 70 coupled with the centrifugal and centripetal action above referred to will effect a thorough cleansing of the bowl. At the same time, the lowering of the level within the tank by opening the ball cock supplies water to the hollow rim and the baffles J therein 75 produce an equal distribution around all sides of said rim. This in turn produces jets of equal force continuing in action during the emptying of the tank and the refilling of the same and furnishing water 80 after the breaking of the siphon for re-establishing the water seal.

What we claim as our invention is:

1. In a water closet, the combination with 85 a bowl, of a flushing tank integral with said bowl and having an apertured bottom approximately at the level of the water seal in said bowl, a channel beneath the bottom of said tank extending to the bowl and opening therein beneath the normal water 90 seal, a flushing valve controlling the aperture in said bottom, and an extension of said channel rising within the tank to above the normal water level therein and open at its upper end to constitute an overflow.

2. In a water closet, the combination with 95 a bowl, a flushing tank integral therewith, of a valve controlled channel connecting said tank with said bowl at a point below the water seal of the latter, and an extension of 100 said channel rising in said tank to a point above the normal level constituting an overflow connection in constant communication with the bowl.

3. In a water closet, the combination with 105 a bowl, a flushing tank integral therewith, of a channel connecting said tank with said bowl having a port opening through the bottom of the tank, a valve for completely closing said port, and an extension of said 110 channel rising to a point above the normal water level in the tank and integral therewith constituting a normal open overflow connection.

4. In a water closet, the combination with 115 a bowl, and a tank integral therewith having a port opening through the bottom thereof, and a channel connecting said port with the bowl extending upward to form an overflow for the tank, of a fitting within the 120 tank surrounding said port, a float valve engaging a seat on said fitting, a stem rising centrally from said float valve, an arm rising from said fitting and forming a bearing with which said stem is slidably engaged, and a 125 trip lever within said tank directly but loosely engaging said stem to lift said valve from its seat without lateral displacement of said stem.

5. In a water closet, the combination with 130

a siphonic action bowl, of a flushing tank for forming a gravity head between the water seal and the top of the bowl, means for discharging water from said tank into the lower portion of the bowl to establish siphonic action, and means for directing the water entering the bowl to produce a whirling action therein limited in velocity to avoid interference with the establishment of siphonic action.

6. In a water closet, the combination with a siphonic action bowl, of a flushing tank for forming a gravity head between the water seal and the top of the bowl, means

for discharging water from said tank into the lower portion of the bowl, to establish siphonic action, said passage having a terminal portion communicating with a port in the side of the bowl and being so fashioned as to direct the water toward the central portion of the mass but sufficiently at one side of the geometric centre to produce a whirling action of limited velocity.

In testimony whereof we affix our signatures.

JAMES M. TEAHEN.
WILLIAM TAYLOR.
